(57) CLAIM

The ornamental design for a mermaid swimsuit, as shown and described.

DESCRIPTION

FIG. 1 is a perspective view of the present invention, showing the mermaid swimsuit of the new design;

FIG. 2 is a front side elevational view thereof;

FIG. 3 is a back side elevational view thereof;

FIG. 4 is a top plan elevational view thereof;

FIG. 5 is a bottom plan elevational view thereof;

FIG. 6 is a right side elevational view thereof; and,

FIG. 7 is a left side elevational view thereof.

The broken lines in FIGS. 1-7 represent stitching.
